MOTOR DRIVEN ICE SKATE

Oren F. Russell, Palmer, Wash.

Application March 25, 1941, Serial No. 385,161

3 Claims. (Cl. 180—6)

The present invention relates to new and useful improvements in ice skates and has for its primary object to provide drive means for the skates embodying a spiral screw mounted at the lower portion of the skate for engaging the ice or other surface over which the skate is traveling and providing a drive connection between the screw and a motor mounted at the rear of the skate for driving the skate over the surface.

A further object of the present invention is to provide adjustable means for the screw by means of which the engagement of the screw with the surface of the ice may be regulated.

A still further object is to provide a skate of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a side elevational view of the ice skate showing the drive screw mounted in position thereon,

Figure 2 is a bottom plan view,

Figure 3 is a side elevational view of the spiral screw providing the propelling means for the skate,

Figure 4 is a sectional view taken substantially on a line 4—4 of Figure 1,

Figure 5 is a horizontal sectional view through one of the adjustable bearing supports for the screw, and

Figure 6 is a detail of one of the bearings for the shaft of the screw.

Referring now to the drawings in detail, wherein for the purpose of illustration I have disclosed a preferred embodiment of the invention, the numeral 5 designates an ice skate which includes the blade 6 formed of front and rear sections 7 and 8, respectively, having their adjacent ends spaced apart as shown to advantage in Figure 1 of the drawings.

Secured to the blade in position between the rear end of the front section 7 and the front end of the rear section 8 is a spiral screw shield 9 which is open at its bottom. Positioned in the housing and welded or otherwise secured to the blade sections is a front bearing guide 10 and a rear bearing guide 11, each of the guides being

enclosed in a housing 12 and formed with a pair of vertically extending opposed grooves 12' within which bearing supporting blocks 13 are slidably mounted. Embedded in each of the blocks 13 is a trunnion 14, the trunnions projecting outwardly from diametrically opposite sides of a bearing 15 within which the shaft 16 of a spiral screw 17 is journaled. The end of the shaft at the front end of the screw is journaled in the front bearing block 10 while the rear end of the screw is journaled in the rear bearing block 11. A stud 18 projects upwardly from the bearing 15 and over which is positioned the lower end of a coil spring 19, the coil spring extending upwardly and has its upper end engaged by a stud 20 formed on the lower end of a head 21 of an adjusting screw 22 which projects upwardly through the top of the housing 12. The top of the shield 9 is formed with a slot 29 providing access to the screws 22. The adjusting screws 22 may thus be employed for adjusting the spiral screw vertically to regulate its engagement with the ice over which the skate is travelling.

A sectional shaft 23 is attached to the rear end of the shaft 16 by means of a universal connection 24, the shaft 23 being journaled in a housing 25 secured to the side of the rear section 8 of the blade. The rear end of the shaft section 23 is provided with an extension shaft 26 also connected to the section 23 by a universal coupling 27, the extension 26 being adapted for connection with the drive shaft of a motor, such as an internal combustion engine adapted for mounting on a platform 28 projecting rearwardly from the rear section 8 of the blade.

From the foregoing it will be apparent that the spiral screw 17 may be driven by the motor at the rear of the skate and thus serve to propel the skate forwardly.

It is believed the details of construction, advantages and manner of use of the device will be readily understood from the foregoing without further detailed explanation.

Having thus described the invention, what I claim is:

1. A motor driven ice skate comprising a spiral screw, means for rotatably mounting the screw on a horizontal longitudinal axis on the blade of the skate, means for vertically adjusting the screw and a motor driven drive shaft operatively connected to the screw.

2. A motor driven ice skate comprising a spiral screw having a shaft at each end, a bearing for each shaft, a guide for each bearing carried by the blade of the skate, means for vertically ad-

justing the bearings in the guides and a flexible drive shaft connection for the screw.

3. A motor driven skate comprising a skate blade formed of front and rear longitudinally spaced sections, a bearing guide secured to the adjacent ends of each section, a bearing slidably positioned in each guide for vertical movement, a spiral screw having its ends journalled in the

respective bearings, a driven shaft operatively connected to the screw, means for securing the bearings in vertically adjusted position and a shield for the screw attached to the skate and having an opening therein providing access to said bearing adjusting means.

OREN F. RUSSELL.
